(57) **CLAIM**

The ornamental design for the protrusions on a belt, as shown and described.

DESCRIPTION

FIG. 1 is a perspective view of the front, right, and top sides of the protrusions on a belt showing my new design; FIG. 2 is a front elevational view thereof; FIG. 3 is a left side elevational view thereof, the right side being a mirror image; FIG. 4 is a top plan view thereof; and, FIG. 5 is a bottom view thereof.

In FIGS. 1–5, the rear surface of the protrusions on a belt, which does not constitute an integral part of the claimed design, is not illustrated. In FIGS. 1–5, any broken line illustration of environmental structure in the drawings is not part of the claimed design.
